UNITED STATES PATENT OFFICE.

CHARLES ALKINS, OF CHICAGO, ILLINOIS, ASSIGNOR TO HENRIETTA ALKINS, OF SAME PLACE.

RAIL-BRACE.

SPECIFICATION forming part of Letters Patent No. 365,222, dated June 21, 1887.

Application filed November 2, 1886. Serial No. 217,845. (No model.)

To all whom it may concern:

Be it known that I, CHARLES ALKINS, a citizen of the United States, residing at Chicago, in the county of Cook and State of Illinois, have invented certain new and useful Improvements in Rail-Braces, of which the following is a specification.

This invention relates to rail-braces adapted for bracing the rails of a railroad, particularly at frogs or switches or at points where bends or curves occur in the road. These braces are constructed with a base portion adapted to be spiked down upon a cross-tie or other appropriate bed, and with a solid abutment rising from said base portion and adapted to fit against the rail.

The objects of my invention are, first, to provide a strong and durable and at the same time a comparatively light construction of rail-brace; second, to lessen their cost by reducing the amount of metal heretofore incident to solid rail-braces without detracting from the strength and durability of the brace; third, to provide a light, strong, economical, and effective construction of brace adapted for application to the rail at a point where a spike for holding down the rail is driven into the cross-tie, and to provide a construction which shall admit of the brace abutting against a rail in a manner to support and strengthen the rail, to hold the rail down upon the cross-tie, to effectively brace the rail against lateral force exerted laterally against the same, and to receive and cover the spike, which is driven into the cross-tie for the purpose of engaging the base of the rail.

To the attainment of the foregoing ends my invention consists in matters hereinafter described, and particularly pointed out in the claims.

A rail-brace constructed in accordance with my invention may be either struck up of wrought or malleable iron or steel, or it may be made of cast iron, steel, or malleable iron, or other suitable metal, it being immaterial whether the brace is cast or struck up from the metals hereinbefore specified or from any other suitable or desirable metal, so long as the prominent features of form or construction hereinafter particularly referred to are preserved.

In my application for Letters Patent filed in the United States, and serially numbered 210,510, I have shown and described a metal rail-brace involving the more prominent features of construction found in the brace forming the subject of this application; but in said first-mentioned application my claims are limited to the method of striking up the brace to a particular form of blank and to a struck-up metal brace having certain distinctive features, good and sufficient reason being therein shown for making said claims. In this application, however, I desire to be understood as not confining myself either to the mode of making the brace or to a struck-up metal brace, but claim the form or construction of the brace as involving the production of a new and improved article.

In the drawings, Figure 1 represents a vertical section taken transversely through a rail and longitudinally through the rail-brace constructed and applied in accordance with my invention, said view also including a portion of the cross-tie. Fig. 2 is a top plan view of said rail-brace, and Fig. 3 is a transverse vertical section thereof, taken on the line *x* *x* of Fig. 2. Fig. 4 is a side view of a portion of the brace.

In said drawings the rail-brace is formed with a base, *A*, and with a hollow abutment, *B*, which rises from the base, and which is adapted at its highest end to fit against and is provided with a seat, *b*, for engaging a portion of the tread of a rail.

The base *A* consists of an oblong plate, which at one end is turned up to some extent, in order to provide its under side with the upwardly-inclined seating portion *a*, which rises from the horizontal under side seating portion, *a'*, of the base-plate, the said inclined seating portion *a* being adapted to seat and snugly fit upon the base portion of the rail, while the base portion *a'* of the brace is adapted to seat and fit upon a cross-tie, as in Fig. 1, wherein *C* indicates a section of an ordinary rail, and *D* a portion of a cross-tie.

The hollow abutment *B* rises centrally from the oblong base portion of the brace—that is to say, it rises along a line between the two opposite longitudinal side edges of said base *A*. In cross section the hollow abutment is proxi-

mately of an inverted **U** or **V** shape, as best illustrated in Fig. 3, wherein the section is taken at a point back of the seat *b*, that is formed at what may be termed the "forward" 5 as well as the "highest" end of the hollow abutment. This construction serves to provide a long hollow abutment, which is in effect arch shaped, and which, while dispensing with the amount of metal that would be required 10 if it were solid, is nevertheless strong and durable. The hollow abutment slopes downwardly from its high end at which the seat *b* is formed toward the rear or opposite end of the brace, the sloping surface along the top 15 side of said abutment terminating at its lowest point near the rear end of the base of the rail-brace—as, for example, at or near the points *b'*, Figs. 1 and 2.

The base portion of the rail-brace is for a 20 portion of its length divided by the oblong concavity of the hollow abutment, which division commences, for example, substantially at or near the point *b'* and continues to the forward end of the brace, it being seen that 25 the side walls, *b'*, of the hollow abutment unite with the base portion at opposite sides of the space or concavity within the hollow abutment.

The hollow abutment can be further strengthened by vertical flanges or ribs *b*³, formed at 30 opposite sides of its forward end, which said ribs merge at their lower ends into the forward portions, *a*, of the base. The forward inclined portions of the base of the rail-brace converge 35 somewhat toward the forward end of the brace, in order to adapt them to set sufficiently close up to the rail, it being observed that by reason of the inclination of the upper side of the base of the rail the brace would strike the rail-base too near the edge thereof if the inclined 40 portions *a* were squared at their corners. It will also be observed that the said inclined portions *a* of the base of the brace are somewhat curved near their union with the horizontal portion of said base, whereby they are 45 particularly adapted to fit the edge of the base of a rail.

The base of this rail-brace is provided at suitable points between its ends with openings 50 *a'*, for spikes or the like, which can be employed for bolting the rail-brace down upon the cross-tie, and at its rear end the base of said rail-brace is provided with an opening or notch, *a*³, for another spike, which can be employed,

as in Fig. 1, for assisting in holding the rail-brace in position. The lower abutting face portion of the seat *b* of the brace slopes downwardly toward the front of the brace, while the abutting face portion of the part or parts *a* of the base of said brace incline upwardly, as 60 hereinbefore specified, whereby the said seating or abutting face portions of the brace constitute, in effect, a wedge at the forward end of the hollow abutment, the portions *a* of the sides of the hollow abutment being in the nature of flanges uniting with the abutment and with the main body of the base of the brace, which said flanges partake of the upward inclination of the lower edges, *b'*, of the hollow abutment illustrated by the sectional view, 65 Fig. 1. By such arrangement I provide a rail-brace having a hollow abutment rising from a base and formed with a wedge-shaped abutting or seating end, which can be wedged in between the tread and the base of a rail, and 70 which also receives a portion of the lower edge corner of the tread of the rail, as clearly indicated in said Fig. 1.

A further advantage of the hollow abutment is that it will receive or straddle a spike employed to bolt the rail down upon the cross-tie, this being also illustrated in Fig. 1, wherein the head of the spike *E* employed to bolt down the rail is shown inclosed and covered by the hollow abutment. 80

What I claim as my invention is—

1. A rail-brace having a hollow abutment rising from a base, substantially as described.
2. The rail-brace provided with a hollow abutment rising from a base, and having its forward abutting end wedge-shaped and adapted to fit against the tread and base of a rail, substantially as described.
3. The rail-brace having the hollow abutment *B*, rising from a base and provided with the abutting or seating portion *b*, said base being provided with the inclined portions *a*, substantially as described.
4. The herein-described rail-brace having a base, *A*, formed with the portions *a* and *a'*, and the hollow abutment *B*, rising from said base and provided with the abutting portions *b* and *b'*, substantially as shown and described, and for the purpose set forth.

CHARLES ALKINS.
